UNITED STATES PATENT OFFICE.

WILLIAM E. BROOKE, OF TRENTON, NEW JERSEY, ASSIGNOR TO THE AMERICAN SAW COMPANY, OF SAME PLACE.

COMBINED WRENCH AND SCREW-DRIVER.

SPECIFICATION forming part of Letters Patent No. 486,759, dated November 22, 1892.

Application filed April 6, 1892. Serial No. 428,036. (No model.)

To all whom it may concern:

Be it known that I, WILLIAM E. BROOKE, a citizen of the United States, residing at Trenton, in the county of Mercer and State of New Jersey, have invented certain new and useful Improvements in a Combined Wrench and Screw-Driver; and I do hereby declare the following to be a full, clear, and exact description of the invention, such as will enable others skilled in the art to which it appertains to make and use the same.

This invention relates to an improvement in a combined wrench and screw-driver, its object being to provide a neat, simple, and efficient combination device for use for various purposes, but more especially useful with bicycles and the invention consists, essentially, in the construction, arrangement, and combination of parts, substantially as will be hereinafter described and claimed.

In the annexed drawings, illustrating my invention, Figure 1 is a plan view of my improved combination wrench and screw-driver, the jaws being closed. Fig. 2 is a longitudinal section of the same. Fig. 3 is a partial longitudinal section and a partial elevational view of the device, the section being taken at right angles to the section of Fig. 2. Fig. 4 is a longitudinal section showing certain modifications. Fig. 5 is a detail plan of the separable screw-threaded shank belonging to the movable jaw.

Similar letters of reference designate corresponding parts throughout the different figures of the drawings.

A denotes the hollow wrench-stock or handle-piece and rigid jaw combined. It is of a flattened elongated form. It may be made in any preferable and desirable manner, being either cast or made of hard sheet metal. Its form and size may vary within considerable limits.

B designates the rigid jaw proper, which is formed as a part of the handle-piece.

45 The movable jaw D, which is parallel to the rigid jaw B and is adjustable away from or toward the latter to permit the use of the device with nuts of varying sizes, is preferably formed on one end with a hammer end d, and this jaw D is made integral with its slid-

ing shank C, which lies within the handle-piece A and conforms to the internal dimensions thereof, being designed to reciprocate back and forth therein in order to accomplish the adjustment of the movable jaw relatively to the position of the rigid jaw. The sliding shank C is provided at its inner end with a screw-threaded-shank C', whereon is a knurled or milled adjusting-nut E, provided with the encircling groove e, which nut is located in a transverse opening in the handle-piece A at a point about midway the length thereof. It will be evident that by rotating the adjusting-nut E within its recess the screw which is in engagement therewith will be fed forward, and the movable jaw consequently adjusted in one direction or the other, as may be desired.

On the inner side of the casing A are formed lugs or projections a a, which enter the groove e in the adjusting-nut, and thereby provide supports for said nuts, so that when strain is thrown upon the adjusting-screw the nut will be held firmly, and thereby the jaws will not be deflected from their normal parallelism sufficiently to destroy the effect of their grip upon the object between them.

The end of the handle-piece A opposite to that which carries the fixed jaw B is provided with a slot k of suitable size to permit the projection therethrough of a screw-driver bit, which is adapted to be located inside of the casing A when it is not needed for use.

F designates the screw-driver. It is formed on its inner end with a screw-threaded shank F', on which is a knurled or milled adjusting-nut G, similar in general purpose and function to that of the adjusting-nut E, said nut G being located likewise in a transverse opening in the handle-piece A at a point a short distance from the end wherein is the slot k. It will be evident that by rotating the adjusting-nut G within its recess the screw which is in engagement therewith will be fed forward and the screw-driver bit consequently projected from or retracted within the end of the main casing. The ends of the screws C' and F' are in contact with each other when the screw-driver is located in its innermost position in the casing, as shown in Figs. 2 and 100

3, and when the movable jaw is likewise closed. In this way I provide a neat, simple, and efficient tool which will be found to have numerous advantages and excellencies in actual use. Many changes may be made in the exact construction and precise arrangement of the parts without going outside of the invention.

In Figs. 4 and 5 I have shown a modification in the construction of certain parts of my improved combined wrench and screw-driver. It will be seen in these figures that instead of having the screw-threaded shank C' integral with the sliding shank C of the movable jaw D, as it is shown in Fig. 2, I make said screw-threaded shank C' separate from the sliding shank C. The purpose of making it separate in this manner is because it is easier to make, the process of manufacturing being simpler. In Fig. 4 it will be seen that the shank C is provided at its inner end with a T-shaped slot, which receives a T-shaped head C², formed on the end of the screw C'. Thus the screw and shank are firmly and easily connected together. It will be found in actual practice that this separate manufacture of these two parts is a desideratum. Likewise it will be seen in Figs. 4 and 5 that instead of having the screw-driver F made integral with its screw-threaded shank F', as it is in Fig. 2, I make the two parts separate. This is done for the purpose of ease and simplicity in the manufacture, just as in the case of the movable jaw-shank. It will be seen that the screw-driver F is provided at its inner end with a T-shaped slot, which receives a T-shaped head F² on the end of the screw-threaded shank F', so that in this way the screw F' and the screw-driver F are tightly and firmly fastened together. When the screw-driver is made in this way, it will be manifest that should the screw-driver break off its corner in use the part F can be detached from the screw F' and a new part F supplied, so that the necessity of making a new screw would be obviated and the expense thereof avoided.

Having thus described my invention, what

I claim as new, and desire to secure by Letters Patent, is—

1. In a combined wrench and screw-driver, the combination of the hollow wrench-stock or handle-piece A, having formed therewith the fixed jaw B, the movable jaw D, having slide C and provided with the internally-located screw-threaded shank C', an adjusting-nut E, located on the said screw-threaded shank within the transverse opening in the handle-piece, said nut being provided with an encircling groove, which is engaged by lugs or projections on the inside of the handle-piece A, the screw-driver F, having the screw-threaded shank F', and the adjusting-nut G, located on said screw-threaded shank, with a transverse opening in the handle-piece, substantially as described.

2. In a combined wrench and screw-driver, the combination of the main wrench-stock or handle-piece A, having formed therewith the fixed jaw B, the movable jaw D, having a slide C located within the handle-piece, on the inner end of which slide is a screw-threaded shank C', an adjusting-nut E on said screw-threaded shank and located within a transverse slot in the main casing, said screw-threaded shank being provided with a T-shaped head C², which enters a T-shaped slot in the end of the slide C in order that they may be detachably connected with each other, a screw-driver F, movable through a slot in the end of the casing opposite to the fixed jaw, said screw-driver being provided at its inner end with a T-shaped slot, a screw-threaded shank F', having a T-shaped head F², which enters said slot in order that the shank and screw-driver may be detachably connected together, and an adjusting-nut on the said screw-threaded shank, located within a transverse opening in the main casing.

In testimony whereof I affix my signature in presence of two witnesses.

WILLIAM E. BROOKE.
